TAPE CARTRIDGE RACK

Robert S. Wallace, Los Angeles, Calif., assignor to Simpac International Inc., Los Angeles, Calif.

Filed June 11, 1973, Ser. No. 369,005

Term of patent 14 years

Int. Cl. D6—04

U.S. Cl. D6—85

FIG. 1 is a perspective view taken from the front, showing the top and one end of a tape cartridge rack, showing my new design;

FIG. 2 is a perspective view taken from the rear, showing the bottom and opposite end thereof.

I claim:

The ornamental design for a tape cartridge rack, substantially as shown and described.
